UNITED STATES PATENT OFFICE.

CHARLES H. LUSH, OF FREEPORT, NEW YORK.

KNOCKDOWN ELECTRIC SIGN.

1,205,767.

Specification of Letters Patent. Patented Nov. 21, 1916.

Application filed October 21, 1915. Serial No. 57,048.

To all whom it may concern:

Be it known that I, CHARLES H. LUSH, a citizen of the United States, and a resident of Freeport, in the county of Nassau and State of New York, have invented a new and Improved Knockdown Electric Sign, of which the following is a full, clear, and exact description.

This invention relates to illuminated signs of that type mounted on a horizontal supporting bar and having both sides visible.

The invention has for its general objects to provide an all-metal double-faced reflector sign which is of comparatively simple and inexpensive construction, of durable and substantial design and capable of being readily taken apart or knocked down for convenience in storing or shipping, and in which the panel is easily removed or interchanged.

With such objects in view and others which will appear as the description proceeds, the invention comprises various novel features of construction and arrangement of parts which will be set forth with particularity in the following description and claims appended hereto.

In the accompanying drawing which illustrates one embodiment of the invention and wherein similar characters of reference indicate corresponding parts in all the views, Figure 1 is a perspective view of the sign; Fig. 2 is a vertical section of the upper portion thereof; Fig. 3 is a perspective view of one of the heads of the hood; Fig. 4 is a perspective view showing one end of the reflector; Fig. 5 is an enlarged sectional view of the panel-holding frame; and Fig. 6 is a detail sectional view on the line 6—6, Fig. 2.

Referring to the drawing, 1 designates a horizontal support in the form of a rod or section of pipe which has one end fastened in a fixed socket 2 secured to a wall or other supporting surface 3, and on the outer end of the rod 1 is a cap-piece 4 from which extend diverging bracing chains or equivalent elements 5.

The sign embodies a panel 6 which may be of sheet metal, glass or other material, and the edge of this panel is set into a U-shaped frame 7 made of a strip having a channel 8 that receives the edges of the panel, there being rubber or equivalent packing material 9 in the channel so as to tightly hold the sign panel 6. The upper extremities of the

side members 10 of the frame 7 pass through a hood 11 and these said upper ends have secured thereto by cotter pins or other removable fastenings 12, T-couplings 13, the upper members 14 of the couplings being slidably fitted on the supporting rod 1, whereby the sign is free to swing with the wind. By taking out the cotter pins the sign consisting of the panel 6, frame 10 and hood 11 is removable as a unit.

The hood 11 consists of an approximately semi-cylindrical sheet metal body 15 removably fitted to heads 16 which have peripheral flanges 17 that embrace over the ends of the hood body 15, and fastening rods 18 pass through beads 19 formed at the horizontal edges of the hood body 15 and also pass through ears or apertured lugs 20 on the corners of the heads 16. Within the hood 11 is a reflector 21 which is constructed of sheet metal and is of V-shaped cross-section, with the members 22 forming reflecting surfaces disposed at a suitable obtuse angle to the plane of the sign panel 6. The lower edges of the reflecting members 22 are connected together by a reentrant portion 23 of inverted U-shaped cross-section which forms a groove or pocket for receiving the upper edge of the sign panel 6, so that the reflector 21 is supported on and grips the sign panel. On the inner face of the head 16 a pair of ribs 24 diverge upwardly with the bottom edge, and the ends of the members 22 engage under these ribs so that the reflector and hood are readily centralized with respect to each other, so as to facilitate the insertion of the extremities of the members 10 of the frame 7 which holds the sign panel 6. The upper portions of the members 10 pass through notches 25 and 26 in the flanges 17 of the hood and reentrant part 23 of the reflector, respectively, as shown in Figs. 3 and 4. Lamps 27 are arranged under the hood and at opposite sides of the plane of the panel, these lamps being preferably carried by the reflecting portions 22 of the reflector. Constructed in this manner the parts of the sign can be easily and quickly put together and no fastenings are required to secure the parts to each other, except the cotter pins 12.

From the foregoing description taken in connection with the accompanying drawing, the advantages of the construction and method of operation will be readily understood by those skilled in the art to which the

invention appertains, and while I have described the principle of operation, together with the device which I now consider to be the best embodiment thereof, I desire to have it understood that the device shown is merely illustrative and that such changes may be made when desired as fall within the scope of the appended claims.

Having thus described my invention, I claim as new and desire to secure by Letters Patent:

1. A sign device comprising a supporting member, a U-shaped frame, a panel having its edges set into the frame, a removable hood disposed over the panel and having openings through which extend the side members of the frame, and a reflector arranged in the hood and supported on the top edge of the panel and supporting the hood.

2. A sign device comprising a panel, a U-shaped frame in which the side and bottom edges of the panel are disposed, a hood through which the side members of the frame extend upwardly, a supporting member to which the side members of the frame are connected, and a V-shaped reflector supported on top of the panel and having its reflecting portion disposed at the opposite sides of the plane of the panel.

3. A sign device comprising a hood having openings at its ends, a V-shaped reflector disposed within and unconnected with the hood and having a reentrant pocket, a sign panel extending into the pocket, whereby the panel supports the reflector in the hood, a frame for supporting the panel and having side members extending through the openings of the hood, and lamps mounted in the hood in coöperative relation with the reflector.

4. A sign device comprising a supporting member, a U-shaped frame detachably con-

nected with and suspended from the member, a sign panel mounted on the frame, a reflector detachably mounted on the panel, a hood disposed over the reflector and detachably mounted on the frame, said hood having openings at its ends through which the side members of the frame extend, and lamps arranged under the hood and in coöperative relation with the reflector, said hood being supported by the reflector and the reflector being supported by the panel.

5. A sign device comprising a hood, a frame having side members extending upwardly through the hood, T-couplings detachably connected with the upper ends of the side members of the frame, a horizontal support extending through the couplings, a sign panel mounted on the frame, a reflector having portions disposed at opposite sides of the plane of the panel and supported on the top edge of the latter, and lamps disposed in coöperative relation with the reflector.

6. A sign device comprising a hood having heads at its ends, ribs on the inner surfaces of the heads and diverging upwardly in V-shaped relation, a V-shaped reflector having its ends engaged under the ribs and provided at its bottom with an upwardly-extending reentrant pocket, a frame having side members extending upwardly through the hood, a panel mounted on the frame and supporting the reflector, and lamps disposed under the hood and in coöperative relation with the reflector.

In testimony whereof I have signed my name to this specification in the presence of two subscribing witnesses.

CHARLES H. LUSH.
